UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 18, 1921. Serial No. 485,691.

To all whom it may concern:

Be it known that I, MORRIS P. HOLMES, a citizen of the United States, residing at Claremont, in the county of Sullivan and 5 State of New Hampshire, have invented certain, new and useful Improvements in Mining Machines, of which the following is a full, clear, and exact specification.

My invention relates to mining machines. 10 It has for its object to provide an improved take-up mechanism for such a machine. A further object of my invention is to provide an improved take-up mechanism especially adapted to cooperate with a continuous flexible feeding member and to be 15 readily adjusted in such a manner as to enable the machine to be angled as desired during its operation in a room or the like. A more specific object of my invention is to 20 provide such an improved take-up mechanism which is especially adapted to be applied to standard machines of the type utilizing a continuous flexible feeding member, without change in the machine or substantial additional expense.

For purposes of illustration I have shown in the accompanying drawings one embodiment which my invention may assume in practice.

30 In these drawings,—

Fig. 1 is a plan view of a mining machine equipped with my improvement.

Fig. 2 is a side elevation of the same, parts being broken away to facilitate illustration.

35 Fig. 3 is a diagrammatic view showing the machine in its different positions during sumping and cutting at the face.

In this illustrative construction I have shown a mining machine comprising a frame 1 and having a cutter bar 2 projecting therefrom and carrying a usual cutter chain 3, the cutter chain being driven by a mining machine motor 4 through suitable mechanism not shown and the mining machine being adapted to be propelled on its own bottom relative to the mine bottom and the flexible feeding member 5, by means of a reversible rotating feed operating member 6, herein carried on a vertical axis at the

50 rear of the machine frame and rotated through suitable motor driven feeding mechanism not shown, the flexible feeding member 5 preferably being suitably reeved about the member 6 and a cooperating idler 7

herein located on a vertical axis in rear of 55 the feed operating member 6.

In my improved construction a take-up member, generally indicated at 8 and of angle form having arms 9 and 10 disposed at an obtuse angle to one another and in the same plane, is pivoted on a pivot pin 11 carried by a bracket 12 suitably attached to the side of the machine frame. As shown, the pivot 11 is slightly inclined to the left in Fig. 2 in order that the member 8 may be 60 disposed at an angle to the horizontal with the free end of its arm 9 adjacent the bottom at the front end of the machine, and the free end of its arm 10 adjacent the plane of the feed operating member at the rear 65 end of the machine frame. Herein it will also be noted that guiding means for the flexible feeding member in the form of idlers 13 and 14 are carried on the extremities of the arms 9 and 10, respectively, and 70 that the ends of the arms 9 and 10 are respectively forked as at 15 and 16 to receive the idlers which are suitably rotatably mounted in the forks as on bolts 17 and 18. Attention is also directed to the fact that 75 the member 8 is provided with parallel upper and lower surfaces connected by a relatively perpendicular web 19 which extends along the arm 9, around the pivot 11, and along the arm 10. It will also be noted that 80 a very rugged pivoted construction is provided, including a substantial pin receiving lug 20 on the bracket 12 received between corresponding substantial pin receiving portions 21, 22 on the member 8. Here attention is also directed to the fact that the web 85 19 on the arm 10 is transversely slotted as at 23 to receive an arcuate laterally extending member 24 formed on a bracket 25 attached to the side of the frame 1 at a point 90 slightly above and in rear of the bracket 12, the disposition of the slot and member 24 being such that the arm 10 may move freely 95 on the member 24 and be clamped in fixed relation thereto in any predetermined position by suitable means, as, for instance, a set screw 26 threaded in the arm and communicating with the slot.

In the operation of my improved construction it will be understood that during 100 sumping the right hand end of the flexible feeding member 5 is connected to the right hand rib as to a jack 27 and that the flexible

feeding member is threaded through the machine and disposed relative to the idler 7, feed operating member 6, and idlers 14 and 13 as illustrated at the right hand side 5 of Fig. 3, the flexible feeding member also being connected to the face as by a jack 28 and the member 8 then having its arm 10 moved in as close as possible to the side of the machine frame and being held in that 10 position by the set screw 26. With the parts thus connected and the machine disposed in rear of the face with the tip of its bar adjacent the latter, it will be evident that upon rotation of the feed operating 15 member 6 in the proper direction and simultaneous operation of the cutter chain, the machine will move toward the face at the angle illustrated in Fig. 3 until it has completed its sumping cut and occupies the position shown at the right hand side of Fig. 20 3. When this cut has been completed, the jack 28 is removed and the then free end of the flexible feeding member is connected at the left hand rib as to the same or another 25 jack 29, the machine then being ready to be swung or straightened into position for its transverse cut. This is accomplished by simply reversing the rotation of the feed operating member and releasing the set 30 screw 26, whereupon it will be evident that the back end of the machine will then be pulled backward toward the right rib about a pivot at the front end in such a manner as to straighten the machine in the cut, the 35 member 8 being simultaneously moved about its pivot in such a manner as to swing the arm 10 further to the left and the arm 9 further to the right relative to the machine frame until the parts reach the position indicated 40 at the center of Fig. 3, when, by simply again setting the set screw 26, the machine will be moved across the face from the position shown at the right hand side of Fig. 3 in the relation to the face and of the 45 parts to one another shown in the center dotted line position of Fig. 3. Obviously, if an obstruction is encountered during crossing the face, the machine may be angled by simply reversing the feed of the feed 50 operating member at any time to swing the rear end of the machine and provide the necessary slack to permit adjustment of the member 8 into such a position as to give the desired angle of the machine. Similarly 55 when the machine has completed its transverse cut, it may be made to finish its cut by angling the machine and adjusting the member 8 into the position shown at the left of Fig. 3 and then connecting the free end of 60 the flexible feeding member to a point in rear of the machine as indicated.

While I have in this application specifically described one form which my invention may assume in practice, it will be understood that this form of the same is shown for

purposes of illustration and that the invention may be modified and embodied in various other forms without departing from its spirit or the scope of the appended claims. 70

What I claim as new and desire to secure by Letters Patent is:

1. In a mining machine, a machine frame 75 slidable upon a mine bottom during cutting and having projecting cutting mechanism, and feeding and guiding mechanism therefor including a feed operating member and a flexible feeding member providing portions extending in opposite directions from points adjacent the opposite ends of said frame and an adjustable takeup member disposed at an angle to the horizontal and presenting guiding means at the opposite ends of said frame with which said flexible feeding member 80 cooperates, one of said guiding means and said feed operating member being so disposed as to be cut by horizontal planes substantially above the plane of said cutting mechanism and the other of said guiding 85 means being cut by horizontal planes cutting said cutting mechanism. 90

2. In a mining machine, a machine frame 95 slidable upon a mine bottom during cutting, feeding and guiding mechanism therefor including a feed operating member and a flexible feeding member cooperating therewith and providing portions extending in opposite directions from points adjacent the opposite ends of said frame, and a take up 100 member presenting guiding means at the opposite ends of said frame and engaging said flexible member wholly at one side of said feed operating member. 100

3. In a mining machine, a machine frame 105 slidable upon a mine bottom during cutting, feeding and guiding mechanism therefor including a feed operating member and a flexible feeding member cooperating therewith and providing portions extending in 110 opposite directions from points adjacent the opposite ends of said frame, and a takeup member presenting guiding means at the opposite ends of said frame and engaging only that portion of the flexible feeding 115 member which lies in advance of the feed operating member in terms of direction of machine travel during cutting across a face. 115

4. In a mining machine, a machine frame 120 slidable upon a mine bottom during cutting, feeding and guiding mechanism therefor including a feed operating member and a flexible feeding member engagable thereby and providing portions extending in opposite directions from points adjacent the opposite 125 end of said frame, and takeup means including a pivoted element having portions at opposite sides of its pivot making a material angle with each other and disposed longitudinally of and adjustable upon said frame 130

- and engaging said flexible feeding member at spaced points wholly to one side of said feed operating member.
5. In a mining machine, a machine frame 5 slidable upon a mine bottom during cutting, feeding and guiding mechanism therefor including a feed operating member and a flexible feeding member providing portions extending in opposite directions from points 10 adjacent the opposite ends of said frame, takeup means including a pivoted element having portions at opposite sides of its pivot making a material angle with each other and disposed longitudinally of and adjustable 15 upon said frame and engaging said flexible feeding member wholly at one side of said feed operating member, and means for holding said takeup member in different positions of adjustment.
- 20 6. In a mining machine, a machine frame slidable upon a mine bottom during cutting, feeding and guiding mechanism therefor including a feed operating member and a flexible feeding member providing portions extending in opposite directions from points 25 adjacent the opposite ends of said frame, and a takeup member including a pivoted element having portions at opposite sides of its pivot making a material angle with each 30 other and disposed longitudinally of and adjustable upon said frame and engaging said flexible feeding member, said takeup member having idlers on its opposite ends engaging said flexible feeding member at spaced 35 points both of which lie in a portion of said member to one side of said feed operating member.
7. In a mining machine, a machine frame 40 slidable upon a mine bottom during cutting, feeding and guiding mechanism therefor including a feed operating member and a flexible feeding member providing portions extending in opposite directions from points 45 adjacent the opposite ends of said frame, and a takeup member disposed longitudinally of said frame and engaging said flexible feeding member, said takeup member being pivoted to said frame substantially midway between its ends and the ends of the 50 frame.
8. In a mining machine, a machine frame 55 slidable on its bottom on a mine bottom during cutting, feeding and guiding mechanism therefor including a feed operating member and a flexible feeding member providing portions extending in opposite directions 60 from points adjacent the opposite ends of said frame, and an angular takeup member disposed longitudinally of said frame and engaging said flexible feeding member, said angular takeup member being pivoted to said frame substantially midway between its ends and the ends of the frame.
9. In a mining machine, a machine frame 65 slidable upon a mine bottom during cutting,
- cutting mechanism carried thereby, feeding and guiding mechanism therefor including a feed operating member rotatable on a vertical axis and in horizontal planes substantially above the plane of said cutting mechanism and a flexible feeding member providing portions extending in opposite directions from points adjacent the opposite ends of said frame, and an adjustable takeup member pivoted on the advance side of said frame and disposed at an angle to the horizontal whereby its opposite ends may be cut by horizontal planes respectively cutting said feed operating member and said cutting mechanism, said takeup member extending to points adjacent the opposite ends of said frame.
10. In a mining machine, a machine frame slidable upon a mine bottom during cutting, cutting mechanism carried thereby, feeding and guiding mechanism therefor including a feed operating member rotatable on a vertical axis and in horizontal planes substantially above the plane of said cutting mechanisms and a flexible feeding member providing portions extending in opposite directions from points adjacent the opposite ends of said frame, and an angular takeup member pivoted on the advancing side of said frame, said takeup member being disposed at an angle to the horizontal whereby its opposite ends may be cut by horizontal planes respectively cutting said feed operating member and said cutting mechanism, said takeup member extending to points adjacent the opposite ends of said frame.
11. In a mining machine, a machine frame slidable upon a mine bottom during cutting, cutting mechanism carried thereby, feeding and guiding mechanism therefor including a feed operating member rotatable on a vertical axis and in horizontal planes substantially above the plane of said cutting mechanism and a flexible feeding member providing portions extending in opposite directions from points adjacent the opposite ends of said frame, an angular takeup member pivoted on the advancing side of said frame, said takeup member being disposed at an angle to the horizontal whereby its opposite ends may be cut by horizontal planes respectively cutting said feed operating member and said cutting mechanism, and said takeup member also extending to points adjacent the opposite ends of said frame, and means for holding said takeup member in different positions of adjustment.
12. In a mining machine, a machine frame slidable upon a mine bottom during cutting, cutting mechanism carried thereby, feeding and guiding mechanism therefor including a feed operating member rotatable on a vertical axis and in horizontal planes substantially above the plane of said cutting mechanism and a flexible feeding member providing portions extending in opposite directions from points adjacent the opposite ends

- of said frame, an angular takeup member pivoted on the advancing side of said frame, said takeup member being disposed at an angle to the horizontal whereby its opposite ends may be cut by horizontal planes respectively cutting said feed operating member and said cutting mechanism, and said takeup member also extending to points adjacent the opposite ends of said frame, and means 10 for holding said takeup member in different positions of adjustment including holding means connected between the rear arm of said takeup member and said frame.
13. In a mining machine, a machine frame 15 slidable upon a mine bottom during cutting, cutting mechanism carried thereby, feeding and guiding mechanism therefor including a feed operating member rotatable on a vertical axis and in horizontal planes substantially above the plane of said cutting mechanism and a flexible feeding member providing portions extending in opposite directions from points adjacent the opposite ends of said frame, an angular takeup member 20 pivoted on the advancing side of said frame, said takeup member being disposed at an angle to the horizontal whereby its opposite ends may be cut by horizontal planes respectively cutting said feed operating 25 member and said cutting mechanism, and said takeup member also extending to points adjacent the opposite ends of said frame, and means for holding said takeup member in different positions of adjustment including 30 an arcuate member and slot connection between the frame and one of the arms.
14. The combination with a mining machine slidable on a mine bottom and having flexible feeding mechanism including flexible 35 feeding portions disposable in opposite directions from opposite ends of the machine body, of an adjustable takeup including an adjustable takeup member carrying a guide sheave from which the advance portion passes directly towards a rib toward which the machine is moving.
15. The combination with a mining machine slidable on a mine bottom and having flexible feeding mechanism including flexible 40 feeding portions disposable in opposite directions from opposite ends of the machine body, of an adjustable takeup including an adjustable takeup member carrying a guide sheave from which the advance portion 45 passes directly to a rib toward which the machine is moving, said takeup member also carrying a guide at the opposite end of the machine body.
16. A mining machine including a frame 50 supporting cutting mechanism slidable laterally on a mine bottom and also including flexible feeding mechanism having flexible feeding portions disposable laterally in opposite directions from opposite ends of the machine body, a feed operating member op-

erative to draw in the advance portion, and means for angling said machine adjustable to change the distance from the frame at which said portion leaves the machine.

17. A mining machine slidable laterally 70 on a mine bottom comprising flexible feeding mechanism including flexible feeding portions disposable laterally in opposite directions from opposite ends of the machine body, and angularly disposed takeup means pivoted intermediate its ends at one side of the machine body and engaging one of said portions at a plurality of longitudinally spaced points.

18. A mining machine slidable laterally 80 on a mine bottom comprising flexible feeding mechanism including flexible feeding portions disposable laterally in opposite directions from opposite ends of the machine body, and angularly disposed takeup means pivoted intermediate its ends at the advancing side of the machine body and engaging one of said portions at a plurality of longitudinally spaced points.

19. A mining machine slidable laterally 90 on a mine bottom comprising flexible feeding mechanism including a continuous flexible feeding member comprising flexible feeding portions disposable laterally in opposite directions from opposite ends of the machine body, and angularly adjustable takeup means engaging one of said portions exclusively and having provision whereby it may be adjusted about a pivot by one of said flexible portions to vary the length of the advance portion of said flexible feeding mechanism without varying similarly the receding portion thereof.

20. A mining machine slidable on a mine bottom comprising flexible feeding mechanism including flexible feeding portions disposable laterally in opposite directions from opposite ends of the machine body, and takeup means on said machine adjustable to vary the effective length of the advance portion of said flexible feeding mechanism without varying similarly the receding portion, said takeup means having means for guiding said advance portion movable away from and toward the longitudinal axis of said machine in a plane extending generally longitudinally of the machine.

21. A mining machine slidable on a mine bottom comprising flexible feeding mechanism including flexible feeding portions disposable laterally in opposite directions from opposite ends of the machine body, and takeup means on said machine adjustable to vary the effective length of the advance portion of said flexible feeding mechanism, said takeup means including a pivoted takeup member having guides engaging the advance portion of said flexible feeding member at a plurality of longitudinally spaced points.

22. A mining machine slideable on a mine bottom comprising flexible feeding mechanism including a continuous flexible member disposable in opposite directions from opposite ends of the machine body, a feed operating member, and takeup means adjustable to vary the effective length of the advance portion of the flexible feeding member while permitting movement of said machine relative thereto, said takeup means including a pivoted takeup member having guides engaging said flexible feeding member at a plurality of longitudinally spaced points and one of said guides forming the portion about which the advance portion of said flexible member is directed laterally to a fixed point extraneous to the machine.
23. A mining machine slideable on a mine bottom and comprising a flexible feeding member including flexible feeding portions

disposable laterally in opposite directions at opposite ends of the machine frame, and a feed operating member cooperating with said flexible feeding member, takeup means including a pivoted element engaging the advance portion of said flexible feeding member at a plurality of points and adapted to be swung when released on rotation of said feed operating member in a direction to move said machine frame forwardly in a direction to diminish the length of the flexible feeding member in advance of said feed operating member and swingable manually on reverse rotation of said feed operating member to take up the slack then inserted in the advance portion of said flexible feeding member.

In testimony whereof I affix my signature.

MORRIS P. HOLMES.
